UNITED STATES PATENT OFFICE.

OSCAR HEYMAN, OF NEW YORK, N. Y.

JEWELRY UNIT AND METHOD AND APPARATUS FOR MAKING THE SAME.

Application filed August 29, 1921. Serial No. 496,242.

To all whom it may concern:

Be it known that I, OSCAR HEYMAN, a citizen of the United States, residing at New York, in the county of New York, State 5 of New York, have invented certain new and useful Improvements in Jewelry Units and Method and Apparatus for Making the Same; and I do hereby declare the following to be a full, clear, and exact description 10 of the invention, such as will enable others skilled in the art to which it appertains to make and use the same.

This invention relates to articulated jewelry, and more particularly to the small box-like units of which such jewelry is made, and to the method of and apparatus for making these units.

In jewelry of this nature, the units are commonly hinged together, and each must 20 therefore be provided with hinge parts, each unit usually having male and female hinge members on opposite ends, designed to cooperate with corresponding members on adjacent units. When working with articles 25 as small as these little box-like units, and especially when they are of noble metal alloys, as they ordinarily must be, the manufacturing difficulties are great. The common method of making these units is to form 30 in the abutting faces of two sections or boxes, half cylindrical recesses adapted to receive small sections of tubing which constitute the knuckles of the hinge. These sections of tubing are secured to the abutting 35 faces of the boxes in such a manner that the sections will fit together in the form of a hinge, a pintle being inserted in the tube sections to unite the parts. The production of units of this type involves a 40 series of delicate welding or soldering operations corresponding to the number of tubular sections to be applied, and the finished articles possess an inherent weakness because the tube sections are separate pieces 45 and are not integral parts of the boxes. Moreover, units made in this manner must be carefully fitted to each other. This is tedious, time-consuming and expensive.

If these units could be made in one piece— 50 hinge knuckles and all—a much stronger article could be obtained, and if they could be made by a die stamping operation, greater accuracy could be realized at much less expense. But to do this has formerly been 55 considered impossible, due in the inherent toughness of the metals and the consequent

difficulty of making clean-cut, sharp-cornered pieces having a deep box-making depression, by any known stamping operations, without running the risk of breaking 60 the die parts and the danger of being unable to strip the dies. It is, therefore, an object of this invention to devise practical ways and means for making these little box units in one piece, particularly out of the 65 noble metal alloys employed in jewelry manufacture.

These alloys, particularly those of platinum-iridium, are so tough that they flow with difficulty in any die, and where the 70 shape involves making a deep depression, as in the manufacture of these box-shaped units, it is practically impossible to employ known methods. Not only is it impossible to make the metal flow into the corners and 75 edges of the die, but the great toughness of the metal inevitably results in breaking the die parts, and many even make it impossible to strip the formed article from the die. This toughness also makes it difficult 80 even to shear a bar of these metals, for the metal tends to pinch and spread. Thus, the problem of fashioning out of these metals such units as those under consideration, and to do it commercially, presents 85 real difficulties. This problem has been finally solved by appreciating necessity for shearing the blank to shape, at the same time forcing it into a die cavity of exactly the same shape, and holding it there tightly 90 confined on all sides during the depression-forming operation. This procedure has made it possible to fashion the blank with accurately dimensioned projections to be shaped later into the male and female hinge 95 knuckles with which each box must be provided. To do all this has necessitated dies of new design, adapted not only to confine the unit being formed, but to eject it upon completion of the operation. Once this 100 blank is made, however, stamped, clean-cut in box form with end projections corresponding to the hinge knuckles, the machining of these projections to final form and the piercing of the bottom of the box to 105 provide a setting for jewels are simple matters. The problem is largely solved when the box-shaped blank is made.

The invention will be more clearly understood after a study of the accompanying 110 drawings in which Fig. 1 is a vertical longitudinal section through the dies employed

in forming the blank. Figs. 2 and 3 are plan views of the male and female die members respectively, taken on line 2-2 and 3-3 of Fig. 1. Fig. 4 is a vertical transverse section through the male die member taken on a plane at right angles to the section plane of Fig. 1. Fig. 5 is a similar view of the female die member. Figs. 6, 7, 8 and 9 are transverse vertical sections on an enlarged scale taken through both die members and showing the successive steps followed in forming the blank. Fig. 10 is a view in perspective of the completed blank as it is ejected from the dies and Figs. 11, 12, 13 and 14 represent the following successive stages in the manufacture of the completed unit.

The blank forming apparatus shown in Figs. 1 to 9 comprise a stationary base 1 and a vertically reciprocating head 2, sliding relative to the base upon vertical guide rods 3 projecting upwardly from the base and secured thereto. The head 2 carries the male die member 4 and the base 1 the female die member 5.

The male die member 4 is carried directly upon a plate 6 depending from the head 2 by means of four bolts 7 secured to the plate 6 but sliding loosely in the head 2. The relative movement between the head and the plate is guided by means of two guide rods 8 secured to the head and projecting downwardly through two corresponding openings in the plate. The plate is normally spaced apart from the head as shown in Fig. 1 by its own weight and also by the expansion of four coil springs 9 which surround the bolts 7.

The male die member 4 is shaped to correspond exactly with the completed blank as shown most clearly in Fig. 2, being shaped on either end to conform to the projections in the blank which subsequently form the hinge knuckles. The center of this die member is formed with a passage 11 square in cross section corresponding to the depression in the completed box. Within this passage a plunger 12 is located. This plunger is supported by a bolt 13 secured to and depending from the head 2 as clearly shown in Figs. 1 and 4. When the head is in its raised position as shown in Fig. 1, the lower end of the plunger 12 is positioned some distance back from the lower opening of the passage 11. When, however, the head is depressed as it is during the normal operation of the machine until the male die member contacts with the stock, the plate 6 is forced upwardly, the springs 9 are compressed and the plunger 12 projects outwardly through the member 4 for a purpose to be described later.

Resting upon the base 1 are two blocks 14 and between them are two plates 15 projecting slightly above the upper faces of the

blocks 14, held against longitudinal movement and reinforced by means of ribs 20. These parts 14 and 15 define the side walls of the female die member. The base of this member is formed by an anvil 16 slidably mounted in the cavity and supported upon a block 17 which is in turn supported upon a cylindrical disc 18 slidably held within a cavity 19 in the base. Projecting through the base and into this cavity 19 are three equi-spaced pins 21 which contact with and support the disc 18. These pins are in turn supported upon a transverse bar 22 which is loosely seated within a corresponding slot 23 in the lower face of the base. This transverse bar 22 is supported by two rods 24 which pass loosely through openings in the base and are fixed to the head 2. One of the blocks 14 is provided on its upper face with a plate 25 provided with a projecting finger 26 which acts as a stop for the metal bar fed forward to the die, and guided by the inner ends of the plates 15.

The method of forming the blanks will be clear from a study of Figs. 6, 7, 8 and 9. A strip of platinum 27 of proper width and thickness is fed forward over the face of the forward block 14 and between the inner beveled ends of plates 15 until it contacts with the finger 26. The male die member and its plunger and the anvil 16 are all in raised position, the relation of the parts being clearly shown in Fig. 6, and also in Fig. 2. The head 2 is then depressed and the descending member 4 shears the bar 27 and at the same time forces the sheared section 27' downwardly into the cavity defined by blocks 14 and plates 15, the anvil following this downward movement as described above. The parts then occupy the position shown in Fig. 7. It will be noted that the plunger 12 is still in its raised or retracted position, which means that the springs 9 have been rigid enough to permit the shearing action to take place without sensibly compressing. The anvil having reached its lower limit, due to the contact of disc 18 with the bottom of the cavity 19, springs 9 compress and downward movement of the male die member stops. But as the head 2 is uninterruptedly continuing to drop the plunger 12 continues in its downward movement and projects beyond the lower face of the member 4 extending a considerable distance into the metal blank 27 as shown in Fig. 8 and forming a depression 28. During this operation the metal is confined with absolute rigidity on 5 sides, the sixth and upper side, however, is held by the member 4 which in turn is resiliently held by springs 9. As the plunger descends the slight flow of the metal in an upward direction forces the plate 6 upwardly against the pressure of springs 9 until it contacts with the head 2. The metal is then under heavy pressure on

all sides and a sharp-cornered blank results. The quantity of metal must, of course, be nicely predetermined or the die will be broken.

5 The head 2 is now retracted. At the start of this upward movement the expansion of the highly compressed springs 9 holds the member 4 in contact with the blank, thus stripping the plunger which follows the head 10 upwardly into its retracted position within the passage 11. Further upward movement of the head raises bar 22 and this through pins 21, disc 18 and block 17 forces the anvil 16 upwardly, which in turn ejects the 15 formed blank as shown in Fig. 9. This blank is removed and the strip 26 fed forward for another operation.

The cutting edge of the member 4, as clearly shown in Fig. 3, is that edge which 20 presents the widest continuous cutting part. With each shearing operation the blank which is forced into the cavity is formed with a projection 29 which corresponds to the male knuckle of the hinge while at the 25 same time the end of the strip 26 is cut with the other corresponding set of projections 30. Upon the succeeding operation these will be moved forward and will accurately fit within in the farther end of the member 5 as shown.

30 By the next operation of the knuckle members are shaped. This may be done as follows: The blanks are placed upon a jig, the depressions in each blank fitting over a corresponding projection of the jig. 35 When a number of these have been thus positioned, the whole is clamped to the bed of a planer and a special shaping tool rounds the projections, first on one end of the box and then on the other, until they 40 assume the shape shown in Fig. 11.

The metal in the side wall of the box between the knuckles of the female hinge member may then be punched out by placing the unit in a press and punching the metal 45 out by means of a plunger. After this operation the blank is as shown in Fig. 12.

The next operation comprises countersinking the sides of the box adjacent the male hinge member to provide suitable recesses for the corresponding knuckles on an 50 adjacent unit. This operation can be carried out in any desired manner, as will be obvious to those skilled in the art. After this is done holes are drilled in both knuckle 55 members for the ultimate reception of the pintle, the completed unit being shown in Fig. 14.

Although a certain specific apparatus has 60 been shown and described in connection with the method of forming these blanks, it will be clear that the invention is not necessarily limited to these structural details and that the device might be modified to perform substantially the same functions without departing from the spirit of the inven-

tion. The invention has also been described as particularly applicable to working with noble metal alloys and it was in this connection that it was developed. It is obvious, however, that softer metals may be 70 worked in this manner, although such a working is not necessary. It is also clear that other metals possessing substantially the same physical properties as these alloys could preferably be worked in this same 75 manner.

I claim:

1. The method of forming box-like jewelry units comprising confining a blank within a die cavity rigidly on five sides and 80 yieldingly on the sixth side and shaping it by means of a plunger introduced through the sixth side.

2. The method of forming jewelry units comprising feeding a strip of metal over the female member of a die, shearing blanks from the strip by means of the male die member, the shearing edges being shaped to give each blank projections for corresponding male and female hinge parts, simultaneously forcing each blank into the cavity defined by the female die member and forming a depression in the blank while so confined. 90

3. The method of forming jewelry units 95 comprising feeding a strip of metal over the female member of a die, shearing blanks from the strip by means of the male die member, the shearing edges being shaped to give each blank projections for corresponding male and female hinge parts, simultaneously forcing each blank into the cavity defined by the female die member, forming a depression in the blank while so confined, 100 ejecting the blank, and shaping the projections to form hinge knuckles. 105

4. Apparatus for forming jewelry unit blanks of the kind described comprising male and female die members shaped to shear off blanks from a metal bar fed between them so that the blanks will be provided with projections from which hinge knuckles can be shaped, the male die member forcing the sheared blank into the cavity defined by the female die member during 110 the shearing operation.

5. Apparatus for forming jewelry unit blanks of the kind described comprising male and female die members designed to form a blank, a movable anvil forming the 115 bottom of the female die member, and means for positively moving the anvil with the retractile movement of the male die member to eject the blank.

6. Apparatus for forming jewelry unit 125 blanks of the kind described comprising male and female die members, a plunger in the male die member movable relative thereto and means causing the plunger to project beyond the end of its die member to stamp 130

a depression in the blank held between the die members.

7. Apparatus for forming jewelry unit blanks of the kind described comprising male and female die members, a plunger in the male die member movable relative thereto for stamping a depression in the blank held between the die members, and means for stripping the plunger.
8. Apparatus for forming jewelry unit blanks of the kind described comprising a base, a head movable thereto, a plate carried by the head, a male die member carried by the plate and having a passage therein, resilient means between the plate and the head permitting slight relative movement between them, a plunger rigidly secured to the head and movable within the passage in the male die member when the resilient means permit relative movement between the plate and the head, and a female die member carried by the base and cooperating with said male die member.
9. Apparatus for forming jewelry unit blanks of the kind described comprising male and female die members, the female die member being defined by two blocks and two plates, the plates extending beyond the

upper face of the blocks and serving as a guideway for the stock from which the 30 blanks are made.

10. An article for use in the manufacture of jewelry comprising a hollow box shaped member having side and end walls, the end walls being provided with hinge members 35 and the entire article including the hinge members being formed out of a single piece of material.

11. An article of jewelry comprising a 40 number of hinged units each having side and end walls, the end walls being provided with projecting pintle receiving knuckles adapted to cooperate with knuckles of adjacent units, the walls and knuckles of each unit being formed out of a single piece of 45 metal.

12. A jewelry unit in the form of a hollow member having formed in one piece with the end walls thereof projecting knuckles 50 adapted to receive pintles, said end walls being provided with depressions adjacent the knuckles within which the cooperating knuckles of an adjacent unit are adapted to fit.

In testimony whereof I affix my signature. 55
OSCAR HEYMAN.
